UNITED STATES PATENT OFFICE

FRANK S. MEES, OF LYNN, MASSACHUSETTS, ASSIGNOR TO NORTH AMERICAN CHEMICAL COMPANY, OF BOSTON, MASSACHUSETTS, A CORPORATION OF MASSACHUSETTS

METHOD OF OUTLINING MCKAY SHOES

Application filed December 31, 1927. Serial No. 243,845.

In order to make a neat McKay shoe, having a first class appearance next to the outer sole, the edge of the upper where it is bent over the innersole is edged, creased, or outlined by an ironing process with a hot iron applied and operated the same as one would iron a garment. This has always been done as a separate operation requiring therefore a separate operator, a separate operating stand and a separate operating tool. My present invention eliminates this extra operator, stand, and tool. At the same time that the bottom filler is laid and spread in the shoe-bottom cavity and the pleated or lapped edges of the upper are waxed, I outline the edge of the upper and I accomplish all this simultaneously with one and the same tool and operation. The McKay shoe might be called the poor man's shoe, and therefore I consider that this material saving in time, labor, and factory equipment is a material contribution toward further reducing the cost of this important class of shoes.

Further advantages of my invention will be pointed out in connection with the following description taken with reference to the accompanying drawing, in which I have illustrated the invention sufficiently to make the same clearly and readily understood.

In the drawings is shown a cross-sectional view of one form of McKay shoe showing the single tool, before mentioned, for accomplishing the outlining of the upper at the same time with the spreading of the filler and waxing of the inturned edges of the upper to render the shoe anti-squeak.

The upper 1 of the shoe on the last 2 is pulled over the edge 3 of the innersole 4 in pleats which are tacked or otherwise secured to the innersole as conventionally illustrated at 5. This forms a shoe-bottom cavity 6 between the exposed side of the innersole and the inturned edges 7 of the upper. Then a spreadable filler piece 8 is put in place and flattened or spread to cavity filling position as indicated in the drawing. This spreading is done by a roll 9 electrically heated by a cartridge unit or any other kind of heater 10, and at the same time that the roll spreads the filler it carries some of the wax from the

filler over onto the crimped inturned edges 11 of the upper to render the shoe anti-squeak at this point which has heretofore caused most of the squeaking common to McKay shoes. It will be understood that by the term 55 waxing I mean to include any anti-squeak coating or application whether of technical wax or otherwise. I make the roll 9 longer than the width of the shoe and preferably slightly flaring as indicated at 12 so that thereby the roll as it goes over the shoe-bottom outlines the edge of the upper at the point 13 where it has always heretofore been ironed as a separate operation. This gives the true, straight, neat outlining or sharply 60 defined corner next to the outer sole when the outer sole is later put in position and secured as the final element in the shoe-bottom. It will be understood that heretofore it has always been the practice to apply the filler 65 to the shoe-bottom and secure it in place. Then the shoe has, as a separate operation, been painted or otherwise waxed along the region 11, and then taken to another stand 70 in the factory where another operator was provided with an electric ironing tool of the same nature as a laundry flat-iron and ironed back and forth. I eliminate all these extra steps and tools and accomplish the entire 75 operation in all three particulars simultaneously by one and the same tool and one and the same operation. By simultaneous I do not mean necessarily to restrict the accomplishment of the three preferable features of filler spreading, anti-squeak waxing, 80 and edge outlining by a single forward or back movement of the roll. No two shoes are exactly the same, as the innersoles differ, the upper leather differs, and, in fact, everything about the shoes differs necessarily 85 in one shoe from another shoe. So it may naturally be found that the operator has to tip his shoe a little with reference to the roll in order to make the outlining true and correct, and especially if a straight roll rather than a flaring roll is employed. Also different operators have their own peculiarities 90 of preference and one operator may prefer to move the shoe with reference to the roll first for the filling operation, devoting his 95 100

strict attention to the bottom cavity to see that he gets the filler spread accurately and then he simply swings the shoe around in contact with the roll for the edging operation. 5 Thus, in any case, the outlining or edge ironing is accomplished at the same time as the filler laying and by the same tool, so that by my process an extra tool is rendered unnecessary and likewise the usual separate 10 operator and separate operation.

It will be observed that I preferably slightly concave the roll 9 at 14 so as to arch the spread filler slightly. This is for the purpose of providing a slight excess of filler 15 so that when the sole is laid and secured to the upper and innersole in usual manner, and then subjected to the bottom leveller, the pressure of the latter will force out this excess of binder into the pleats of the inturned upper 20 and between said upper and the outer sole so as to unite all the parts of the bottom to function substantially as a single unit.

What I claim as my invention is,

1. The herein described method, in connection with the manufacture of a shoe of the kind having an inturned upper around a bottom cavity, consisting of spreading the 25 filler layer thereby waxing the inturned upper around the bottom cavity and outlining 30 the edge of the upper all at the same time and as a part of one and the same bottom forming operation.

2. The herein described method, in connection with the manufacture of a McKay shoe, 35 which consists of outlining the upper of a shoe-bottom and at the same time and as part of the same bottom forming operation laying 40 the filler.

3. The herein described method, in connection 45 with the manufacture of a shoe of the kind having an inturned upper around the bottom, consisting of outlining the upper about the bottom of the shoe and at the same time waxing the inturned crimped portions 50 of the upper.

4. The herein described method, in connection 55 with the manufacture of a McKay shoe, consisting of simultaneously outlining the upper about the bottom of the shoe and spreading the 60 filler in the bottom cavity.

5. The herein described method, in connection 65 with the manufacture of a shoe of the kind having an inturned upper around the bottom cavity, consisting of simultaneously with a hot roll outlining the upper about the 70 bottom of the shoe and spreading the filler in the bottom cavity.

6. The herein described method, in connection 75 with the manufacture of a shoe of the kind having an inturned upper around the bottom cavity, consisting of simultaneously with a single tool outlining the upper about the 80 bottom of the shoe and spreading the 85 filler in the bottom cavity and causing an 90 ironing contact of said tool with the upper in said outlining action.

7. The herein described method, in connection 95 with the manufacture of a shoe, consisting of simultaneously with a single hot tool outlining the upper about the bottom of the 100 shoe and spreading the filler in the bottom cavity and causing an ironing contact of said tool with the upper in said outlining action.

Signed by me at Lynn, Mass., this twenty-eighth day of December, 1927.

FRANK S. MEES.
